CLAIM

U.S. PATENT DOCUMENTS

The ornamental design for a face for a concrete wall block,
as shown and described.

415,773 A * 11/1889 Fiske ..... D25/151 X
D22,610 S * 7/1893 Deslauriers ..... D25/151 X
1,963,966 A * 6/1934 Bennett ..... D25/151 X
2,718,674 A * 9/1955 Hinds ..... D25/151 X
2,819,495 A * 1/1958 Krausz ..... 52/314 X
D379,669 S * 6/1997 Karanikas D25/113

DESCRIPTION

FIG. 1 is a perspective of a face for a concrete wall block as
seen from the lower front center of the face showing my new
design;

FIG. 2 is a perspective view thereof as seen from the front
left side;

FIG. 3 is a perspective view thereof as seen from the front
right side; and,

FIG. 4 is a perspective view thereof as seen from the upper
front center of the face.
